UNITED STATES PATENT OFFICE.

WALTON C. FERRIS, OF LINCOLN, NEBRASKA, ASSIGNOR TO NATIONAL MANUFACTURING COMPANY INC., OF LINCOLN, NEBRASKA, A CORPORATION OF NEBRASKA.

SCAFFOLD HOIST.

Application filed March 16, 1926. Serial No. 95,077.

My present invention relates to scaffold hoists and is in the nature of improvement on the scaffold hoist as set forth in my prior Patent No. 1,577,617, granted March 23, 5 1926. The present invention has for its object the provision of a lever device for elevating the platform, the lever device being of the utmost simplicity both in construction and manipulation and possessing a degree of safety not attained by even the lifting device set forth in my prior patent. It is a further object of my invention to provide such a design in the lever device that greater flexibility may be obtained in the 10 degree of lifting of the platform since individual preferences and special circumstances very often determine the best height to which the platform should be lifted during each individual operation.

Having in view these objects and others which will be mentioned in the following description, I will now refer to the drawings, in which—

Figure 1 is a view in elevation of a single scaffold unit complete and with the overhead protection frame.

Figure 2 is a side view in end elevation of the same.

Figure 3 is a detail view in elevation of the cage assembly.

Figure 4 is a detail view in elevation of a portion of the lifting lever in engagement and ready to be actuated.

Figure 5 is a detail view of the dog or pawl.

Figure 5^a is a detail view of the connector 28.

Figure 6 is an illustration of the lowering tool.

Figure 7 is a view in elevation of a portion of the scaffold unit showing a modified form of the lifting lever and connections.

Figure 8 is a view in elevation showing the modified form of carriage with dogs for engaging the pins.

Figure 9 is a plan view of the lever 21 showing the bifurcated construction of the lever.

Figure 10 is a view in plan of the casting 14 and showing particularly the vertical opening through which the chain 10 passes.

As in the construction shown in my prior

patent, I employ the "pin-drop" type of chain, and since this is fully described in 55 my patent, I will but briefly refer to it in this connection. The chain consists of a plurality of rod-like links 10 connected end to end in such a way that the chain may be easily folded for storage and transportation 60 and as easily unfolded for use. At spaced uniform intervals, preferably six inches, the chain is provided with pins 11 which project from both sides thereof, these pins being either formed integral with the chain or 65 driven through suitable apertures in the chain.

The putlog 12, the plank retainers 13 and in fact all parts of the platform are similar in construction to these parts as shown 70 in my prior patent. At each corner of the platform is a casting 14, there being a pair of castings 14 for each end putlog 12. The castings 14 are each provided with a central aperture as shown in Fig. 10 for receiving 75 the chain 10 which slides freely therethrough. A pair of channel iron members 15 is secured in upright position to each casting 14 and at their upper extremities they receive between the members of the pair a 80 dog cage as shown in Figure 3.

The cage 16 is substantially rectangular in form and is provided with a plurality of dogs 17. The number of these dogs may be varied as desired, but for obvious reasons 85 an even number of dogs is preferable. They may be arranged so that two dogs of each pair are opposite each other and so that they simultaneously fall in operative position against the two projecting portions of a pin 90 11 or they may be staggered so that the two dogs of each pair will alternately and successively engage the projecting ends of the pin. These dogs are all spring pressed inwardly as shown in Figure 3. As shown 95 in Figure 5 the dogs are provided with a channelled portion 17^a and a notched portion 17^b for positively engaging the pin 11. The springs 18 are coiled about the axes 19 on which the dogs 17 are pivoted. One end 100 of each spring is anchored in the cage 17 as shown in Figure 3 and the other end passes through a suitable aperture in the dog as shown in Figures 3 and 5. It will thus be seen that the entire weight of the 105 platform is sustained by the dogs engaging

the pins 11. The inclination of the dogs with reference to the perpendicular as shown in Figure 3 is important. The thrust on the dogs is very largely in a vertical direction 5 so that there is little chance of slippage. The weight of the platform acting through the pins 11 on the dogs tends to force their lower ends inwardly and into firmer engagement with the pins, but if the dogs were 10 given a much greater inclination than that shown in Figure 3, two objections would develop. The dogs must engage the pins 11 but it would be a source of annoyance if they were so inclined that they would engage the 15 link plate connecting the links of the chain. Aside from this the thrust would be directed more in a horizontal direction than is necessary. The dogs are rounded and V-shaped at their noses. The rounded nose of the dog 20 causes it to slide more readily over the surface of the chain support 10 and particularly over any irregularities on the chain support. The V-shaped end tends to make the engagement of the dog with the pins 25 more secure and to align and to keep aligned the pins. The tendency of any chain support is to twist slightly and this tendency is corrected by the V-shaped noses of the dogs 17. The action of the lifting lever 20 also tends to keep the pins in alignment because it straddles the chain and because of the action of the fulcrum seat 21^a.

The casting 14 also has integral therewith an upstanding portion spaced slightly from 35 the members 15. This upstanding portion comprises mainly a transverse web having a curved rib on each side thereof. The curvature of the rib 20 is shown in Figures 1 and 4. The rib is designed to serve as a hook 40 for engaging the end of the lifting lever. The rib may be formed into a single hook or into a plurality of hooks depending on the degree of lift desired for each stroke of the lever. In my drawings and especially in 45 Figure 1, I have shown the rib as provided with two hook shaped portions which each provide a lift of three inches when used with the particular chain and dog construction which I have described. The lever itself is 50 shown in Figure 4. The lever is forked to straddle the chain 10 and the web portion of the casting 14. At 21^a the lever is provided with a socket fulcrum for engaging the pin 11 and at its outer extremity it has 55 a hook portion 21^b for engaging the rib 20. A lever extension 22 may be firmly secured to the lever 21 or it may be provided to serve as a detachable accessory in the form of a piece of gas pipe or the like.

60 From the foregoing description the method of operation may be easily understood. The workman on the platform simply places the lever 21 in engagement with the upper hook of the rib 20, the fulcrum being 65 on the nearest pin 11. A slight pressure

on the lever extension 22 thus raises the platform so that one of the upper pins 11 is engaged by one of the pairs of dogs 17. In my preferred construction the pairs of dogs 17 are spaced equally with the hooks on the 70 rib 20 so that a single lift on one of the hooks will raise the platform a distance equal to one half of the distance between successive pins 11. If it is then desired to give an additional lift to the platform, the inner end 75 of the lever is lifted to bring the hooked end 21^b of the lever into engagement with the lower hook of the rib 20 as shown in Figure 1, and the corner of the platform may thus be given a full lift from pin to pin of the 80 chain with two simple strokes of the lever 21 and with the expenditure of very little time and effort. It is of course understood that in the ordinary practice two workmen are provided with levers which they actuate 85 simultaneously on opposite sides of the platform so that there will be no transverse tilting of the platform.

The cage 16 has integral therewith an outwardly and laterally extending ear 23, and the ear 23 is provided with an elongated aperture 24. The upright 25 is formed from channelled steel and is connected to the ear 23 by means of a detachable pin 26 to permit folding of the upright 25 against the member 15. The aperture 24 is elongated so as to permit insertion of a guard-rail or cable or rope. The pair of uprights 25 is connected to the horizontal overhead beam 27, a special form of connection being used for this purpose as shown in Figures 1 and 2 and 5^a. The connector 28 has the general shape of an hour glass and it permits the passage therethrough of the chain 10 while the platform is being elevated. The connector 28 has a pair of spaced inner ears 29 and a pair of outer ears 30. The ears 30 are secured to and within the channel upright 25 while the ears 29 are secured to the horizontal beam 27 and on the two sides thereof. One of the connecting pins may be a rivet but the other should be a bolt or other detachable connection. As shown in Figure 5^a the connector 28 is formed in two parts and when the bolt is removed one of the parts may be swung on its connection to release the chain 10. This is important in assembling and taking down the overhead protection frame.

In Figure 7 is shown a modified form of 120 the invention. In this case there is a freely moving dog cage 31 which supplements the cage 16. The cage 31 like the cage 16 may be provided with any desired number of dogs 17'. At the bottom of the cage 31 is a link 32 having a lever 33 pivotally connected at its lower end. The lever 33 is pivotally connected at its outer end to the casting 34 which corresponds in a general way to the casting 14 shown in the other drawings. In 125 130

this modified form the lever is always in place since it is part of the apparatus and it cannot become lost. In this case also the lever extension may be either permanently or detachably secured to the lever.

When it is desired to lower the platform it is only necessary to spread a pair of the locking dogs 17 while holding the end of the lever to prevent too sudden a drop. In 10 the construction as described the drop can be only three inches when the second pair of locking dogs engages the pin 11. The lowering therefore must be gradual since the process must be repeated each three inches 15 until the platform has been lowered the desired distance. While the dogs 17 are easily spread by the fingers, I have provided a special tool 35 as shown in Figure 6 for spreading the dogs. This tool is a fork with a pair 20 of beveled tines and it may be thrust into the dog cage at 36 straddling the chain 10 so as to spread the dogs of a pair, whereupon the weight of the platform carries it 25 downwardly to the next pin 11, the drop being checked by the use of the lever 21. The tool 35 is formed by casting or stamping, and preferably with the instructions as shown in Figure 6 so as to make it "fool proof."

30 Especial attention is called to the form of the cage 16 and its relation to the dogs 17. The cage is in general rectangular in shape, but its upper lateral edges are beveled, this being the final but important point in the 35 safety of the scaffold hoist above described. The pair of dogs is wedged into engagement with the chain 10 and a pin 11. If one of these dogs should break or if its spring should become inoperative, the other dog 40 alone has an ample margin of safety to hold the weight of its portion of the platform, and it cannot slip because it is still wedged against the chain and the pin although the wedging angle of the dog has been changed. 45 If a pair of the dogs should become entirely inoperative, the worst that can happen is that the one corner of the platform will fall three inches, or to the point where the second pair of dogs engages a pin 11. Even in 50 the almost impossible event that all of the dogs become crushed and their lower portions become broken, they will still be in wedging engagement with the chain. As long as only a fragment of one of the dogs 55 of the upper pair remains, its jagged edges will be forced into direct engagement with the chain which is thus wedged against the inclined wall on the opposite edge of the cage. The inclined walls at the top of the cage have also a second but very important function in shedding chunks of mortar and particles of stone and thus preventing their entrance into the cage where they would 60 tend to clog the dogs and corrode the mechanism.

The element of safety has been the primary consideration in the development of the present scaffold hoist. Aside from the actual safety provided, there is the idea of safety impressed on the workmen, and this 70 is a psychological factor in the efficiency of the workmen. For example, when they look downward from a platform which is elevated by winding a cable on a drum, the workmen are apt to see only a very hard 75 concrete sidewalk a hundred feet below. With the present scaffold hoist, however, they see the chains reaching to the ground, and a veritable forest of pins confronts them, every one of which is designed for 80 their safety. The fact that the hoisting mechanism is one of extreme simplicity is also a factor of great importance from both the mechanical and the psychological standpoint. Moreover, the simplicity of design 85 leaves the platform clear for the workmen and the materials.

Having thus described my invention in such full, clear, and exact terms that its construction and operation will be readily understood by others skilled in the art to which it pertains, what I claim as new and desire to secure by Letters Patent of the United States is:

1. A scaffold hoist including a platform 95 and a support therefor, said support being adapted to be suspended from an outrigger on a building structure, a hook projecting upwardly from said platform, means consisting of a rigid lever adapted to engage 100 said support and said hook to raise said platform on said support, and means on said platform for automatically engaging said support when the platform has been elevated a predetermined distance.

2. A scaffold hoist including a platform and a support therefor, said support being adapted to be suspended from an outrigger on a building structure, a hooked member on said platform, means consisting of a 110 rigid lever for engaging said support and said platform to elevate said platform on said support, and means on said platform for engaging said hooked member when the platform has been elevated a predetermined 115 distance, said means being adapted to prevent the lowering of said platform after the disengagement of said lever.

3. A scaffold hoist including a platform and a vertically disposed support therefor, 120 said support being adapted to be suspended from a building structure in spaced relation to a wall thereof and being provided with a plurality of abutments at uniformly spaced intervals throughout its length, a plurality 125 of dogs secured to said platform in vertical and spaced apart relation, each of said dogs being adapted to releasably engage one of said abutments to prevent downward movement of the platform, and means for lifting 130

said platform such a distance that the next dog of said plurality of dogs will engage the contiguous higher of said abutments.

4. A scaffold hoist including a platform and a support therefor, said support being adapted to be suspended in vertical position from an outrigger on a building structure and being provided with a plurality of abutments at uniformly spaced intervals throughout its length, a plurality of pairs of dogs secured to said platform, each of said pairs of dogs being adapted to releasably engage one of said abutments to prevent downward movement of said platform, and means for lifting said platform a distance such that a second pair of said dogs will engage the next higher of said abutments.

5. A scaffold hoist including a platform and a support therefor, said support being adapted to be suspended in vertical position from an outrigger on a building structure and being provided with a plurality of abutments uniformly spaced throughout its length, a standard on said platform, said standard being provided with means for guiding said platform in its movements on said support, a plurality of pairs of dogs pivotally secured to said standard at its upper extremity, each of said pairs of dogs

being adapted to releasably engage one of said abutments to prevent downward movement of said platform, and means for lifting said platform a distance such that a second pair of said dogs will engage the next higher of said abutments.

6. A scaffold hoist including a platform and a support therefor, said support being adapted to be suspended in vertical position from an outrigger on a building structure and being provided with a plurality of abutments at uniformly spaced intervals throughout the length thereof, a standard on said platform, a plurality of pairs of dogs on said standard at its upper extremity, each of said pairs of dogs being adapted to successively engage said abutments on said support to prevent downward movement of said platform, means for releasing said dogs from engagement with the abutment to permit downward movement of the platform, and means for lifting said platform a distance such that a second pair of said dogs will engage the next higher of said abutments, said last named means being adapted to be used to retard the descent of said platform when said dogs are released from engagement with the abutment.

In testimony whereof I affix my signature.

WALTON C. FERRIS.
